DANIEL DETRICH BEENKEN, OF SANTA BARBARA, CALIFORNIA.

MULTIPLE-RECORD PHONOGRAPH.

Application filed January 29, 1923. Serial No. 615,662.

My invention relates to improvements in phonographs and it consists of the constructions, combinations and mode of operation herein described and claimed.

5 An object of the invention is to provide a phonograph which is capable of playing more than one record in succession, repeat the successive playing as many times as may be desired and perform all of the functions necessary to changing the records, placing the tone arm and reproducer in position, starting the turntable, etc., automatically.

Another object of the invention is to provide a phonograph of the foregoing description which has only two visible control means, namely, one, an electric starting and stopping switch, the other, a lever which is movable to regulate the playing from 10" to 12" records.

20 Other objects and advantages will appear in the following specification, reference being had to the accompanying drawings, in which:

Fig. 1 is a perspective view of a phonograph constructed in accordance with the invention, the parts being in such positions as though the second record were being played,

Fig. 2 is a horizontal section on the line 2—2 of Fig. 1,

30 Fig. 3 is a view largely in side elevation but which, for the purpose of fixing its relation in respect to Fig. 1, may be described as a section on the line 3—3,

Fig. 4 is a plan view on the order of Fig. 2, the turntable being omitted so as to reveal the mechanism underneath,

Fig. 5 is a detail section of the auxiliary clutch by which the raising and lowering of the carrier stack and the swinging of the carriers is controlled,

40 Fig. 6 is a cross section on the line 6—6 of Fig. 4,

Fig. 7 is a plan view showing the swinging cam in the position opposite to that in Fig. 4, this being the position at which the carrier is swung back into the stack.

50 Fig. 8 is a detail perspective view of the timing drive gears by which the operation of the auxiliary clutch in Fig. 5 is controlled whether the phonograph be adjusted to play 10" or 12" records.

Fig. 9 is a detail longitudinal section on the line 9—9 of Fig. 4,

55 Fig. 10 is a cross section on the line 10—10 of Fig. 4,

Fig. 11 is a section on the line 11—11 of Fig. 4,

Fig. 12 is a section on the line 12—12 of Fig. 4,

Fig. 13 is a detail perspective view of the 60 spring plate in the turntable clutch in Fig. 11,

Fig. 14 is a section on the line 14—14 of Fig. 3, showing some of the internal mechanism of the carrier stack.

65 Fig. 15 is a sectional view showing the rack in a position in which the carrier stack is at the limit, the last record has been played and the stack is about to gravitate to the original or repeating position,

70 Fig. 16 is a detail perspective view of the yoke which forms part of the stack mechanism,

Fig. 17 is a detail perspective view of one of the carrier holders, the relationship of 75 Figs. 16 and 17 being such as to readily suggest how the lug on the yoke engages the abutment on the holder to turn the latter,

Fig. 18 is a perspective view of one of the 80 record carriers,

Fig. 19 is a section taken substantially on the line 19—19 of Fig. 1 (behind the tone arm), the tone arm, driving motor, etc., however, being shown in elevation,

85 Fig. 20 is a detail side elevation showing how the flange on the carrier engages the finger on the tone arm to move the latter to the starting position as the carrier moves into position over the turntable,

Fig. 21 is a detail longitudinal section of 90 the tone arm showing the construction of the parts which carry the finger,

Fig. 22 is a cross section on the line 22—22 of Fig. 21,

Fig. 23 is a section on the line 23—23 of 95 Fig. 4, showing the construction of the auxiliary electric switch,

Fig. 24 is a section on the line 24—24 of Fig. 23,

Fig. 25 is a diagram of the electrical circuits showing how the driving motor is controlled both by the manual electric switch (one of the visible elements referred to) and by the auxiliary electric switch in Fig. 23,

100 Fig. 26 (Sheet 2) is a detail side elevation showing the turntable in the lowered position as distinguished from Fig. 3 in which the turntable is in the raised or playing position, and

105 Figs. 27 and 28 are diagrams illustrating 110

the action of the main and counter shaft gears in performing the record changing operation.

By way of introduction, the attention of the reader is directed to Fig. 1 which shows the general visible arrangement of a phonograph constructed to play twelve records. The individual records are carried by carriers which are arranged in a stack at the left side of the cabinet. The records themselves are omitted from the illustration, but the reader can readily imagine them in place.

Disposed at the right of the carrier stack is the turntable of the phonograph. It is the function of one of the carriers to go through the following cycle of operations: The carrier swings around over the turntable; the turntable is raised to lift the record off of the carrier and simultaneously with this operation, contact of the record is made with the needle, and the turntable starts to revolve and continues revolving until the playing of the record is finished; the turntable lowers so as to replace the record on the carrier, the carrier is swung back into the stack, and the entire stack is then raised sufficiently high to permit the next lowest carrier to swing out over the turntable.

The foregoing cycle of operations is repeated in respect to each carrier until the entire stack of records is played, whereupon the entire stack lowers to the original position and all of the cycles of operation are repeated unless the operator opens the main electric switch. In such event, the phonograph will stop playing after the playing of the record then in position is finished. The reader can hardly appreciate the significance of the acts enumerated above in advance of understanding the following description, and therefore, attention is now directed to the general construction which is followed by a description of the details of construction and that in turn is followed by a description of the operation. The records to be played are fitted into carriers 1, 2, 3, 4, 5, 6, 7, 8, 9, 10, 11, and 12. One of these is shown in detail in Fig. 18. The carriers, and naturally the records, which are intended to be carried thereby, are normally arranged in a stack at the left of the turntable 13.

The turntable shaft 14 is capable of raising and lowering and in so doing, takes the turntable with it. The turntable must be in the lowered position (Fig. 26) in order to permit the carrier 2 (used as an example of one of the carriers) to swing a record into position over the turntable.

This swinging of the carrier 2 is accomplished by a yoke 15 (Figs. 2, 3, 4, 14 and 16). The yoke has a lug 16. The respective carriers 1, 2, etc. are mounted on holders

17, 18, 19, 20, 21, 22, 23, 24, 25, 26, 27 and 28 (Fig. 3). Each of these holders has abutments 29 (Figs. 2 and 17) which are spaced apart to provide a recess 30 with which the lug 16 enters in locking engagement to turn the holder around horizontally when the yoke is turned. This also turns the carrier, and the degree of turning movement, from the record stack to the turntable is approximately 90° (Fig. 2).

There is a crank 31 at the bottom of the yoke 15. A link 32 (Fig. 4) connects the crank to the swinging lever 33. This lever has a pin 34 (which may include a roller) occupying a cam groove 35 in the cam drum 36. The drum is fixed upon a countershaft 37 and when this shaft is made to revolve, so as to turn the cam groove 35 from the position in Fig. 7, to the position in Fig. 4, the yoke 15 is moved through one-quarter of a circle from the full line position in Fig. 7 to the full line position in Fig. 4 and the carrier 2 is transported from the stack to the position over the turntable 13, as stated before.

All this happens while the turntable 13 is in the lowered position. It is necessary to start the stylus 38 of the reproducer 39 (Figs. 1 and 2) at the beginning of the record. The stylus stops near the center of a record at the end of a playing operation, and it is necessary to get it back to the edge before the playing of the second record can be begun. For this purpose, each of the carriers 1, 2, etc., has a flange 40 at the edge nearest to the turntable. The tone arm 41 carries a finger 43.

As the carrier 2 sweeps across to the position over the turntable 13 where the record is intended to be, the flange 40 engages the finger 43 and moves the tone arm over into the position in Figs. 1 and 2. There is nothing to obstruct the passage of the tone arm and its carried parts to this position because the reader must remember that the turntable is still in the lowered position and the carrier operates in a plane too far down to interfere (compare Figs. 19 and 20). It is also necessary to note that when the turntable 13 is lowered, the record is entirely out of range of the stylus 38 (examine the dotted and full line positions in Fig. 19), and it is not until the turntable is raised that the stylus engages the record in readiness to play.

The next act is to raise the turntable 13. This is done by the raising lever 44 (Figs. 11 and 26). This lever is carried by a shaft 45 which, at the other end, has an arm 46 with a roller 47 in engagement with the cam 48 which oscillates the arm. When this cam is in the position in Fig. 26, the turntable 13 is lowered. When it is in the position in Figs. 6 and 11, the turntable is raised.

The reciprocating cam 48 (so called be-

cause of its function) is fixed upon the main shaft 49 which actually consists of two parts, the other part being designated 50 in Fig. 9. There is a reason for the distinction; the part 49 is driven only intermittently, while the part 50 is driven continuously while the phonograph is in operation.

For this purpose, the shaft 50 carries a master gear 51 (Figs. 9, 10 and 11) with which a driving worm gear 52 meshes. This gear is revolved by a driven worm gear 53, which in turn is driven by a worm pinion 54 on the shaft 55 of the motor 56. Carried with the master gear 41, by virtue of being mounted on the same shaft 50, are timing drive gears 57 and 58. Each drive gear has a pair of teeth 59 and 60 respectively, the teeth of each pair being disposed diametrically opposite each other; as plainly shown in Figs. 8 and 11.

That portion of the shaft 50 upon which the timing drive gears are mounted, is made non-circular as at 61 (Fig. 9). The purpose of this arrangement is to permit sliding the gears on the shaft but at the same time compel them to turn with the shaft. The gears are made in one piece, there being a connecting collar 62 provided with an annular groove 63 which is occupied by the shifting yoke 64. This yoke has connections 65 and 66 (Fig. 3) to a lever 67 by means of which the timing gears may either be slid into the position in Fig. 9, or into the opposite position on the shaft, the respective positions representing the setting of the mechanism for playing 10" and 12" records.

When the timing drive gears are shifted back to the position in Fig. 9, the teeth 59 are in registration with the tooth recesses 68 of a star wheel 69. This star wheel is loose on a shaft 70, and this shaft carries a second star wheel 71 which is precisely like the wheel 69 excepting that it has eleven tooth recesses 72 instead of nine tooth recesses as in the wheel 69. The timing drive gears being shifted, as stated, bring the gear 58 to a position where the teeth 60 are out of registration with the star wheel 71 (Fig. 3) and therefore, according to the situation under description, it is only the teeth 59 which are effective in turning the wheel 69, the other star wheel 71 remaining idle.

Continuous rotation of the gear 57 produces an intermittent movement of the star wheel 69 by virtue of the periodic engagement of the teeth 59 with the recesses 68 (Fig. 10). There is a pin 73 on the wheel 69, and a corresponding pin 74 (Fig. 3) on the wheel 71, and as the former ultimately engages the heel 75 of the clutch lever 76, a turning movement of the clutch lever and its supporting shaft 77 is produced. The upper end of this lever 76 then presses in on a clutch dog 78 (Fig. 5) so that engagement with one or the other of a pair of

clutch lugs 79 on the master gear 51 is made. The aforesaid continuous movement of the master gear is now imparted to the main shaft part 49 so as to revolve the reciprocating cam 48 from the position in Fig. 26 to 70 that in Figs. 6 and 11 to cause the rocking of the raising lever 44 and the consequent raising of the turntable 13.

As the turntable nears the limit of the raising movement, contact of the record with the stylus 38 is made. The turntable 13 then begins to revolve. This is accomplished by the tightening of the elements of the friction clutch 80 (Fig. 11) which follows as a result of the upward pressure of the raising lever 44. The clutch lever 76 disengages the dog 78 by virtue of its tendency to gravitate to the right (Figs. 11 and 12) as soon as the pin 73 passes the heel 75. The extension main shaft 49 comes to a standstill after 85 having made one complete revolution. The disengagement of the clutch dog 78 is caused by a spring 81 pressing outward on a plug 82 and in turn against the clutch dog when the dog reaches a lateral passage which it 90 is adapted to normally occupy. It is then that the shaft 49 stops after the aforesaid complete revolution.

As the playing of the record continues, successive engagements of the recesses 68 of the star wheel 69 by the teeth 59 of the gear 57 move the pin 73 around into another engagement with the heel 75 (Fig. 10). The clutch lever 76 thereupon again moves the clutch dog 78 (Fig. 5) into the path of the lugs 79 on the master gear 71, and the extension main shaft 49 makes another revolution as before. The reciprocating cam 48 departs from the arm 46 (Fig. 6) and the turntable lowers to the original position in 105 Fig. 26.

With this lowering act, the played record is re-deposited upon the carrier 2. The stylus 38 remains suspended near the center of the turntable where the playing stops. As soon as the turntable has been lowered, the carrier 2 is swung back into the original position in the carrier stock, and when the carrier has assumed its proper place, the entire stack is raised sufficiently far to bring 110 the carrier 3 into the position formerly occupied by the carrier 2. This is accomplished in this way:

The extension main shaft 49 carries a drive gear 83 (Fig. 6) which of course begins to revolve as soon as the cam 48 begins to revolve. But this gear has a blank space 84 which delays the rotation of the idler 85 and driven gear 86 until the turntable has been fully lowered. Thereupon, engagement 125 of the idler 85 by the gear 83 begins and the countershaft 37, by which the gear 86 is carried, begins to revolve.

The countershaft 37 makes a full revolution in a counterclockwise direction looking 130

from a position in Fig. 6. The first 90° of rotational movement of the shaft 37 is occupied in swinging the carrier 2 from the position in Fig. 4 to that in Fig. 7. The next 5 90° of movement is occupied by the lifting dog 87 in raising the rack 88 the distance between a pair of the teeth 89 as the reader will quite readily understand from Fig. 14. The distance through which the rack is 10 raised, is sufficient to bring the carrier 3 into position to swing out over the turntable at the proper time. The rack is carried by a part of the carrier stack and of necessity, the raising of the rack must raise the carrier 15 stack. The next half revolution of the shaft 37 is occupied in shifting the swinging lever 33 back to the position in Fig. 4, and this time it is the carrier 3 which swings over the turntable with the next record to be 20 played. Attention is next directed to the detailed construction which introduces elements which must necessarily be described so as to make the understanding of the invention clear. The foregoing mechanism is carried 25 by a phonograph cabinet 90. There is a depression 91 on one side for the accommodation of the carrier stack and a closed compartment 92 on the other side for the housing of the operating mechanism, as suggested by Fig. 3. Each carrier is made exactly like the next. The carrier may be pressed out of sheet metal to form a vertical wall 93 and an inturned flange 94 to receive and support a record. The supporting part 30 of the carrier is circular, and is sufficiently larger than a semi-circle to prevent the record slipping out edgewise at the open front.

At the back, the carrier has a pair of lugs 95 and an opening 96. The lugs 95 are 40 adapted to enter the corresponding openings 97 (Figs. 3 and 17) in the vertical wall 98 of the holder 18, and the opening 96 is adapted to receive the lug 99 on the front of the shelf 100. That part of the holder 45 that has the wall 98 and shelf 100 extends out at one side of the otherwise circular holder (see Figs. 2, 4 and 17) so as to make it very easy to fix the carriers in place. The carriers ordinarily are intended to remain 50 in place when once applied unless it be desired to change the phonograph for playing 12" records. In this event, larger carriers are employed but as these are in all respects (except in size) the same as the carriers already described, additional illustration 55 is doubtless unnecessary.

The sides 101 (Fig. 17) engage the in-turned edges 102 of the hood 103 (Figs. 2 and 4) and the holders are thereby guided 60 in the up and down movement of the carrier stack. It is not until one of the holders and carriers (18 and 2, for example) reach the slot 104 in the hood 103 that the carrier and holder may be swung out toward the turntable 13.

A hollow vertical shaft 105 carries a sleeve 106 upon which the holders 17, 18, etc. are mounted. These holders are not mounted directly upon the sleeve but through the medium of plates 107 which have collars 108 70 in contact with the sleeve. The lowermost plate of the series rests on a support 109. The collar of each plate engages the plate next succeeding and a cover 110 binds them all firmly together. This cover is screwed 75 into place on the upper end of the sleeve 106 and is locked in position by a jamb nut 111.

The individual holders rotate upon the collars 108, and felt or other suitable friction washers 112 are fitted in the spaces 80 adjacent to the holders and plates 107. The hollow shaft 105 is fixed at the top of the hood 103 by the plug 113 and nut 114. The plug includes a smooth portion upon which the yoke 15 revolves. There is a similar 85 arrangement at the bottom. A plug 115 both fixes the lower end of the shaft 105 and provides a bottom bearing for the yoke.

A dash pot 116 depends from the plate 117 in which the bottom plug 115 is fastened. A 90 piston 118 operates in the dash pot. The passage of air into and out of the dash pot is controlled by a valve 119 which may be adjusted to vary the size of the orifice. Connection is made between the piston 118 and 95 rack 88 so that the two move together. The action of the dash pot retards the gravitation of the carrier stack when the last record is played and the mechanism is about to readjust itself to repeat a cycle of playing 100 operations. The rack is affixed to the bottom support 109 as shown in Fig. 3.

A bearing plate 120, at one side of the rack 88 (Figs. 3 and 15), provides a support for one end of the countershaft 37, a 105 pawl 121 and latch 122. The pawl 121 furnishes a back check for the rack 88 and supports it in position after the lifting dog 87 departs from engagement with one of the teeth 89 after having lifted the rack and the 110 carrier stack as described above. A spring 123 presses the pawl into the engaging position.

The pawl 121 has a heel 124 which is adapted to be lifted into engagement by the 115 latch 122 by a pin 125 on one side of the rack after the last record has been played and the lifting dog 87 performs its function for the last time in respect to the stack of records then in the process of carrying out a cycle of 120 operation. Upon occurrence of this event the pin 125 raises the heel 124 into engagement with the latch 122 and the pawl 121 125 out of engagement with the teeth of the rack. The lifting dog 87, in completing its revolution, departs from the rack and so leaves the latter unsupported.

Thereupon the rack and the stack of records and carriers gravitate toward the original position, and as soon as the stud 126 130

(near the top of the rack) reaches the heel 127 of the latch 122, the latch is rocked from engagement with the heel 124 of the pawl, and the pawl re-engages the rack as shown in Fig. 14. The engagement at that time will be with the rack tooth 89 next highest up, thereby representing the first holder 17 and carrier 1 to be in position to swing out of the slot 104 and over the turntable 13.

10 Mention of the edges 102 of the hood 103 being turned in to form guides, has been made. These guides occur at the sides of a vertical opening through which the supporting shelves 100 of the holders on the inside 15 of the hood extend. As the holders move well below the hood 103 (Fig. 3) to reach the original or starting position, it is necessary that the guides 102 also extend at least as far as the lower extremity of the holder 20 stack and preferably all the way to the supporting plate 117. The manner of forming and arranging the guides is immaterial.

Mounted on the countershaft 37 is a switch cam 128 (Figs. 3, 4, 23 and 24). This cam 25 makes a complete revolution with each corresponding revolution of the shaft, and in doing so, both opens and closes the automatic electric switch 129. Consider the diagram in Fig. 25. The motor 56 receives current 30 from the wires 130 and 131 of any suitable current force. Arranged in series with one of the wires and in parallel in respect to each other, are the main electric switch 132 and the automatic electric switch 129. As 35 long as the main switch 132 remains closed, the opening of the automatic switch 129 will not interrupt the flow of current to the driving motor, but should the switch 132 be opened, a succeeding opening of the automatic switch 129 (which opening occurs periodically) will interrupt the flow of current so that the driving motor must stop.

This is what actually happens when the operator desires to stop the phonograph. 45 He may desire to stop the phonograph while a record is still being played. The playing will continue until the end of the record is reached, and when the mechanism operates to swing that record back into the stack (Fig. 50 7), which act represents 180° of angular motion of the shaft 37 from the position in Fig. 4, the switch cam 128 will assume a corresponding relative position, in other words, the dotted line position rather than the full 55 line position in Fig. 25. Both electric switches will then be open and the phonograph will stop.

The automatic electric switch comprises a 60 pair of terminals 133 between which the contactor 134 is adapted to move to complete the current path. This contactor is carried by an armature 135 which is urged upwardly by a spring 136 but is pressed downwardly by the engagement of the cam 128 with a 65 button 137 extending up from the armature.

Bearings 138, 139, 140 and 141 (Figs. 3 and 9) furnish the supports for the various shafts involved. The bearing 138 furnishes the support for one end of the countershaft 37 and also for one end of the extension main 70 shaft 49. At one side of the bearing 138, there is an enlargement 142 (Fig. 3) by which the idler 85 (Fig. 6) is supported. Carried by the extension shaft 49 outside of the bearing 139 is a coupling head 143 which 75 carries the dog 78 (Fig. 5) forming part of the auxiliary clutch referred to in the first part of the description above. This clutch is an auxiliary to the main clutch 80 (Fig. 11), the latter controlling the turning of the 80 turntable, the former the swinging of the record carriers, the elevation and depression of the stack and the operation of the automatic electric switch. One side of the coupling 143 is cut out at 144 to make room for 85 the dog 78 which is movably mounted at 145 on the coupling. Both the spring 81 and plug 82, which act to press the dog outwardly, are fitted in a bore 146 in the large 90 part of the coupling.

The free end of the clutch dog normally occupies the lateral passage 146 of a circular opening 147 of a standard 148, in which circular opening the clutch lugs 79 of the master gear 51 rotate. As long as the dog occupies 95 the lateral passage, the clutch lugs have no engagement with the dog, but as soon as the clutch lever 76 presses the dog inwardly, such engagement is established and the extension main shaft 49 caused to rotate with 100 the main shaft 50.

The worm 52 (Fig. 11) which drives the master gear 51, is supported by a circular casing 149 and a plurality of screws 150, these respective parts acting as spacers between the worms 52 and 53. The casing also houses the friction clutch which, as stated above, does not operate to drive the turntable 105 shaft 14 until the friction disks of which it is composed, are pressed together by the 110 raising lever 44.

A supporting plate 151 is one of the elements of the friction clutch. This plate rests on the shoulder provided by the bearing plug 152 in which the lowermost end 115 of the shaft 14 is fixed. A spring plate 153 (Fig. 13) rests on the supporting plate, and it is through this spring plate that the proper tension, necessary for the functioning of the friction clutch 80, is obtained. Ball bearings 154 and 155 are provided for the turntable 120 shaft 14 and for the worm gears 53 and 52 respectively.

The ball bearings 155 run in races formed in the turntable standard 156. This part is 125 a fixture and is made so by being suitably secured to the base plate 117. As has been stated before, the worm gears 52 and 53 run continuously while the phonograph is in operation. This is also true of the main shaft 120.

50 and its carried parts. The turntable shaft 14, on the other hand, rotates only while a record is being played. A portion of the bearing plug 152 occupies the bearing cup 157 by which the bearing ball 154 is contained. This cup has lugs traversed by a pin 158 with which the bifurcated end of the lever 44 has engagement.

Reference is again made to the timing 10 drive gears 57 and 58. These are cast en bloc as shown in Fig. 9. When the lever 67 (Figs. 1, 2 and 3) is shifted to the left, the timing gear 57 occupies a position in registration with the star wheel 69. The phonograph is now adjusted to play 10" records.

The turntable 13 rotates at 80 R. P. M. for three and one-half minutes if a 10" record is to be played, and in that time, the master gear 51 and the driving gear 57 will 20 have made a sufficient number of revolutions to have advanced the pin 73 (Fig. 10) into engagement with the heel 75 of the clutch lever 76. The reader will remember that the star wheel 69 is moved intermittently by 25 the periodic engagements of the teeth 59 with the tooth recesses 68 in the star wheel 69, this number being in proper proportion to the three and one-half minutes playing period of a 10" record. Should the phonograph be set for playing 12" records, the lever 67 should be shifted toward the right so that the timer driving gear 58 is brought into registration with the star wheel 71. The drawings do not show the gear 58 in 30 such driving engagement, but the reader can readily understand how this is accomplished by examining Figs. 3 and 4. The periodic engagements of the teeth 60 of the gear 58 then become effective in moving the star wheel 71. This wheel has eleven tooth recesses corresponding to the longer playing period of the 12" record.

It requires approximately four and one-half minutes to play such a record, and in 45 this time, the star wheel 71 will have made one revolution and the pin 74 will have been advanced far enough to engage the heel 75 of the clutch lever 76. When this gear is engaged and the clutch lever 76 is rocked, 50 the clutch dog 78 (Fig. 5) is thrown into engagement with the clutch lugs 79 so that the extension main shaft 49 begins to revolve with the main shaft 50. This causes the turntable 13 to be lowered, the carrier 2 55 with the played record to swing back into the stack, the elevation of the stack so that carrier 3 occupies the position formerly occupied by carrier 2 and causes the carrier 3 to be swung out over the turntable.

60 The tone arm 42 is made in two parts, namely, the part 42, described before, and a part 159 which is hinged at 160 on the part 42 so as to be capable of slight upward movement with the record when the turntable 13

is raised as in Fig. 19. A bracket 161 is 65 carried by the tone arm part 42. This bracket has a slot 162 in the free end (Fig. 21) so as to make room for the movement of the finger 43 which is pivoted on the bracket at 163. The extremity 43a of the finger is laterally hinged to permit free inward 70 swinging as the carrier sweeps away over the turntable.

A spring 164 presses down on a lug at the rear end of the finger so as not only to keep 75 the finger in engagement with the movable part 159 of the tone arm, but also to follow that part through the slot 162 when it is rocked on its hinges 160 when the turntable is raised. The purpose of this provision is 80 to insure getting the finger 43 out of the way of the record and of the turntable, and Fig. 19 shows how the finger clears the record.

The operation is now reviewed so as to 85 describe the occurrences in a cycle of operation in the sequence by which they happen. Assume the carrier 2 to be in the position around the turntable 13 (Figs. 1 and 2), the turntable 13 to be raised and rotating (Fig. 90 19) and the stylus 38 as approaching the center as the playing of the record progresses.

The reciprocating cam 48 stands in the position shown in Figs. 6, 27 and 11. The extension main shaft 49 by which it is carried, is stationary. The cam 48 holds the turntable up (see Fig. 11). The master gear 51 is, however, rotating in the counterclockwise direction, as it does continuously as 100 long as the phonograph is playing. By repeated engagements of the timing gear teeth 59 of the gear 57 with the recesses 68 of the star wheel 69 (Fig. 10), the pin 73 will ultimately reach the heel 75 and shift the 105 clutch lever 76 in, so as to move the clutch dog 78 into engagement with the nearest of the lugs 79 on the revolving master gear 51.

This establishes a connection between the master gear and the extension shaft 49 so 110 that the latter too begins to rotate. Mention must be made of the fact that approximately three-fourths of a revolution of the shaft 49 equals a full revolution of the countershaft 37. This motion is imparted to the countershaft by means of the mutilated gear 83 on the shaft 49, the idler 85 and the gear 86.

The circumference of the gear 86 corresponds in length to that of the toothed portion of the gear 83, and in order to make it easier for the reader to follow the happenings in the revolution of the counter shaft 37, quarter-revolutions of the gear 86 are marked on the gear 83 in this wise: 0, 1/4, 120 2/4, 3/4 and 4/4. Consider Fig. 4. The swinging lever 33 is inclined toward the right, having been moved to that position 125

by the depression in the cam groove 35, and consequently, the carrier 2 occupies the position around the turntable, as stated before.

Imagine the rotation of the shaft 49 as having begun. The reader will remember that the dog 78 was moved in. As soon as the cam 48 departs from beneath the roller 47 (Fig. 11) the turntable 13 must lower. The shaft 49 makes almost a quarter revolution before the zero mark on the gear 83 reaches the idler 85, and when it does, rotation of the counter shaft 37 begins. Fig. 28 shows how the cams and gears would stand at the present time.

13 Consider a quarter space on the gear 83 as being the same as a quarter revolution of the gear 86. The first quarter revolution (up to the mark 1/4) will move the swinging lever 33 into the position in Fig. 7. The carrier 2 is now swung back into the stack. Now consider the shaft 37 as moving through the second quarter and up to the mark 2/4 on the gears.

Originally the lifting dog 87 (Fig. 14) stood in the position marked 0. The first quarter revolution moved it up 90° to the mark 1/4 into engagement with the nearest tooth 89 of the rack 88. We are now considering the second quarter of revolution of the shaft 37. Remember that the carrier 2 is back in the stack. The lifting dog 87 now lifts the entire stack so as to bring carrier 3 with its record into the position formerly occupied by carrier 2.

35 Now imagine the third quarter of revolution of the shaft 37 as taking place, occupying the gear 83 up to the mark 3/4. It is in this quarter that the automatic electric switch 129 is opened by the switch cam 128.

40 The reader will now understand that had the operator opened the manual switch 132 in Fig. 25 (or, what is the same thing, pressed one of the buttons 165 in Figs. 1 and 2,), at any time during the foregoing playing of the record on carrier 2, the electrical circuit (Fig. 25) would now be opened at both switches 129 and 132, and the phonograph would have stopped with the next carrier and a new record in position to be swung out over the turntable upon a subsequent closure of the switch 132.

But consider the mark 3/4 as having come into alignment with the idler 85. The shaft 37 has made three-quarters of a revolution. The depression of the cam groove 35 has reached the position nearest the observer in Fig. 7 so that it has only one more quarter of a revolution to make in order to complete the full revolution of the shaft 37.

60 Picture this last quarter of a revolution as taking place, the gear 83 being utilized up to the mark 4/4 which is the end of the gear. This last quarter revolution of the shaft 37 is occupied in conveying the cam depression from the position in Fig. 7, to

that in Fig. 4, by which act carrier 3 is swung back into a position over the turntable 13. Compare the full line position of the carrier with the dotted line position of the turntable in Fig. 19. This is the relation that the two bear to each other at the present time.

As the end of the gear 83 has been reached, so far as the idler 85 and gear 86 are concerned, the rotation of the countershaft 37 must stop. But the shaft 49 has not completed a full revolution. The cam 48 is approximately $22\frac{1}{2}$ degrees from its original position in Figs. 6, 11 and 27, and accordingly, the shaft 49 has $22\frac{1}{2}$ degrees more of angular movement to make before the cam 48 reaches that position, and before the clutch dog 78 reaches the lateral passage 146.

In this $22\frac{1}{2}$ degrees of movement, the cam 48 engages the roller 47, rocks the raising lever 44, raises the turntable 13 and lifts the new record off of the waiting carrier 3. As soon as the dog 78 reaches the passage 146, the spring 81 presses the dog out and so the rotation of the shaft 49 stops. The upward pressure of the lever 44 in raising the turntable causes the clutch 80 to start the shaft 14 turning so that the reproduction of the record is begun.

Revert to the time when the pin 73 (Fig. 10) threw the clutch belt 78 in. That happened when the stylus 38 reached the end of the record, at which time the tone arm 42 was directed toward the observer in Fig. 1. The lowering of the turntable and record left the reproducer suspended in a corresponding position and quite out of the way of any adjacent moving part.

Revert next to the time when the countershaft 37 made its last quarter revolution from the position in Fig. 7 to that in Fig. 4. As the carrier 3 was swung out over the turntable, the flange 40 at one side of the carrier engaged the finger 43 (Fig. 19) pendent from the tone arm and caused the tone arm to move back to the position in Fig. 1, so that the stylus 38 stood over the beginning of the sound groove on the record. The subsequent raising of the turntable and record in the last $22\frac{1}{2}$ degrees of angular movement of the cam 48 and shaft 49 brought the record into engagement with the stylus 38 for the beginning of the playing.

It will be evident to the reader that the axial line of the cam 48 (Fig. 6) coincides with the lateral passage 146 (Fig. 12) when the cam reaches its final position in which the turntable stands raised. It should also be evident that the clutch dog 78 occupies a position other than that in Figs. 5 and 12 at the time when the 3/4 mark on the gear 83 comes into registration with the idler 85.

This is so because the dog is diametrically

opposite to the cam 48, in fact being situated on the axial line thereof, and therefore when the cam 48 stands in the position in Fig. 26, the dog 78 occupies a position in the circular opening 147 (Fig. 12) diametrically opposite. As long as the dog is within the circular opening, a clutch connection between the master gear 51 and the shaft 49 is maintained.

Mention was made above of the automatic switch 129 stopping the phonograph at the $3/4$ mark in Fig. 26. It is quite obvious that when the phonograph is started again, the foregoing clutch connection will be maintained through the next $112\frac{1}{2}$ degrees of angular movement of the shaft 49, this representing the last quarter of operation of the gear 83 (up to the $4/4$ mark) and the aforementioned $22\frac{1}{2}$ degrees of movement of the cam 48 to reach the final position in Fig. 6.

Repeated periodic revolutions of the shaft 37 and of the lifting dog 87 (Fig. 14) will ultimately elevate the rack 88 to such a position wherein the last carrier 12 and its record comes into registration with the outlet opening 104 in the hood 103 (Fig. 1). After playing the last record, the clutch dog 78 will be thrown in as before, the turntable will lower, the shaft 37 will revolve and the lifting dog 87 (Fig. 14) will engage the next to the last rack tooth 89 in Fig. 15 after the first quarter revolution of the shaft.

Upon making the next quarter revolution, the lifting dog 87 departs from the rack. The pin 125 will have released the pawl 121 so that the rack 88 and the entire stack of carriers and records is free to gravitate to the bottom, the gravitating motion being retarded by the dash pot 116 and piston 118. The stud 126 behind the rack engages and releases the latch 122 so that the pawl 121 is freed in time to engage the uppermost tooth 89 of the rack 88 and thereby hold carrier 1 in position to be swung out over the turntable. This is done by the last quarter of the gear 83.

While the construction and arrangement of the improved multiple record phonograph as herein described and claimed, is that of a generally preferred form, obviously modifications and changes may be made without departing from the spirit of the invention or the scope of the claims.

I claim:

1. A phonograph comprising a turntable adapted to rotate in the raised one of two positions, a clutch associated with the shaft of the turntable, means which both holds the turntable raised and the clutch in engagement so that there may be rotation, a carrier occupying a waiting position beneath the turntable, means setting the holding means into operation to lower the turntable, deposit a record on the carrier and unclutch the turntable shaft so that rotation stops, and

means connected with the foregoing operating means becoming operative after these acts are performed to swing the carrier to one side.

2. A phonograph comprising a turntable, a stack of record carriers at one side, a main shaft which is driven continuously, an extension main shaft adapted to be clutched to the main shaft, means associated with the extension shaft to then lower the turntable from a raised rotating position so that a record is deposited on a waiting carrier, a countershaft, and means to set said countershaft in revolution after a predetermined revolution of the extension shaft, means associated with the countershaft to initially swing the waiting carrier back into the stack, and other means associated with the countershaft to raise the stack and bring the succeeding carrier into a swinging position.

3. A phonograph comprising a turntable on a shaft, continuously revolving means including a clutch for the shaft, a main shaft which is continuously revolved by said means, an extension shaft, means causing the clutch to grip the main shaft after a predetermined number of revolutions of the main shaft, and means which holds the shaft clutch in an active position prior to the clutching of the extension shaft so that the turntable rotates but which means following said clutching operation releases the shaft clutch and causes the turntable to remain inactive for a complete revolution of the extension shaft.

4. A phonograph comprising a turntable on a shaft, continuously revolving means including a clutch for the shaft, a main shaft which is continuously revolved by said means, a cam having associated means which holds the shaft clutch in an active position so that the turntable rotates, an extension shaft by which the cam is carried, and means to clutch the extension shaft to the main shaft causing the cam to actuate the associated means and release the shaft clutch.

5. A phonograph comprising a turntable on a shaft, continuously revolving means including a clutch for the shaft, a main shaft which is continuously revolved by said means, a cam having associated means which holds the shaft clutch in an active position so that the turntable rotates, an extension shaft by which the cam is carried, means to clutch the extension and main shafts together, means which is operated after a predetermined period of revolution of the main shaft to throw the extension shaft clutch in and thereby actuate said associated means to release the turntable shaft clutch and stop the turntable for a predetermined period of revolution of the extension shaft.

6. A phonograph having a turntable on a shaft, revolving means including a clutch for the shaft, means pressing up on the shaft

to both hold the clutch in and raise the turntable during rotation, a cam adapted to remain stationary to maintain the holding means in position, and means causing the cam to move through a predetermined zone and thereby lower the turntable shaft and release the clutch then again raise the shaft and apply the clutch.

6 7. A phonograph comprising a turntable 10 on a shaft, continuously revolving means including a clutch for the shaft, means to hold the turntable raised and the clutch in engagement to rotate the shaft from said means, and means which advances by a step 15 motion and after a predetermined period causes the holding means to lower the turntable and disengage the clutch so that rotation stops.

8. A phonograph comprising a turntable 20 on a shaft, continuously revolving means including a clutch for the shaft, means which is revolved by said continuously revolving means, means which holds the turntable raised and the clutch in engagement to rotate the turntable shaft from said continuously revolving means, and means which is advanced by a step motion from said revolved means to cause the holding means to lower the turntable and disengage the clutch 30 after a predetermined period of step motion.

9. A phonograph comprising a turntable on a shaft, a clutch by which the shaft is caused to revolve, means including a cam to hold the clutch in engagement, a clutch dog to cause the cam to make a complete cycle of motion wherein the holding means both disengages and reengages said shaft clutch, and means which advances with a step motion and periodically actuates the clutch dog 40 and cause recurrences of the function of said holding means.

10. A phonograph comprising intermittently movable means, continuously movable 45 means including means by which said intermittent motion is produced, a clutch dog adapted to be actuated after a predetermined period of intermittent motion, an associated cam which is stationary prior to said actuation, a turntable shaft having a clutch, and means which is controlled by the cam holding the clutch in engagement while the cam is stationary but causing the disengagement of the clutch upon actuation 55 of said clutch dog and consequent movement of the cam.

11. A phonograph comprising intermittently movable means, continuously movable means including means by which said intermittent motion is produced, a shaft carrying a cam both being adapted to remain stationary, an associated clutch dog adapted to be actuated by said intermittently movable means after a predetermined period of 60 movement to thereby connect the shaft with

said continuously movable means, a turntable shaft having a clutch, and means which is controlled by the cam holding the clutch in engagement while the cam and shaft are stationary but causing the disengagement of 70 the clutch when the cam recedes from the controlling means.

12. A phonograph comprising a turntable on a shaft, a clutch for the shaft, a star wheel having a pin, continuously movable means 75 including means to periodically engage the star wheel and produce an intermittent movement of the pin, a lever, a cam adapted to remain stationary and engage the lever to hold the clutch in an operative position, a clutch dog associated with said continuously movable means, and a clutch lever adapted to be moved by the pin to actuate the clutch dog and cause the movement of the cam for the release of the shaft clutch. 85

13. A phonograph including a continuously movable means including a master gear, a clutch lug on the gear, a stationary shaft having a cam, a clutch dog supported by the shaft and including means to disengage the 90 dog from said lug, and means to shift the dog to engage the lug at a predetermined time thereby carrying the shaft and cam with said continuously movable means.

14. A phonograph including a continuously movable master gear, a star wheel having a pin, means associated with the gear periodically engaging the star wheel to advance the pin, a clutch lug carried by the gear, a shaft having a cam and a clutch dog 100 all adapted to remain stationary, and a clutch lever adapted to be engaged by the pin to shift the dog against the lug for rotation of the shaft and cam with the gear.

15. A phonograph including a continuously movable master gear, a star wheel having a pin, means associated with the gear periodically engaging the star wheel to advance the pin, a clutch lug carried by the gear, a shaft having a cam and a clutch dog 110 all adapted to remain stationary, a clutch lever adapted to be engaged by the pin to shift the dog against the lug for rotation of the shaft and cam with the gear, and means permitting said shaft and cam to perform 115 only a predetermined amount of revolution and then permit the dog to disengage from the lug.

16. A phonograph including a continuously revolvable master gear having a clutch lug, a standard having a circular opening in which the clutch lug revolves and a lateral passage, a shaft having a cam and a clutch dog the latter occupying said passage as the shaft and cam are adapted to remain stationary, and means to shift the dog from said passage into the opening for engagement by the lug which engagement is maintained by the wall of the opening until the passage is again reached. 120 125 130

17. A phonograph including a continuously revolvable main shaft, a master gear having a clutch lug carried by the shaft, a stationary extension shaft having a cam and 5 a clutch dog, a standard having a circular opening in which the clutch lug revolves and a lateral passage occupied by the dog at one side of the path of movement of the lug, a turntable which is adapted to occupy a 10 raised position, a clutch associated with the shaft of the turntable, means associated both with the cam and the turntable by which the clutch is held engaged and the turntable raised while the cam is stationary, and 15 means actuated by the master gear to move the dog into said opening causing the extension shaft to partake of a complete revolution of the main shaft until said passage is again reached during which revolution 20 the turntable is lowered, stopped, raised, and again started by virtue of the functions of the cam and said associated means.
18. A phonograph comprising a turntable occupying the raised one of two positions 25 while playing a record, a carrier in a waiting position below the turntable, a stack of carriers at one side of the turntable out of which the aforesaid carrier is swung, continuously revolvable means, an associated 30 stationary shaft having a cam, means held in one position by the cam to hold the turntable in the raised position, means actuated by said revolvable means to set the shaft in motion so that the cam causes the lowering 35 of the turntable and the deposit of the record on the carrier, and a countershaft which is set in motion after a predetermined movement of the associated shaft, said countershaft having means causing the carrier to 40 swing back into the stack.
19. A phonograph comprising a turntable, means to raise the turntable to a playing position and lower the turntable to an inactive position, a continuously revolvable 45 main shaft, and a periodically revolvable extension shaft with connecting clutch means from which the raising and lowering motion is derived, a countershaft adapted to be set in revolution after a predetermined 50 degree of movement of the extension shaft, a stack of record carriers at one side of the turntable, and means on the countershaft having connections with the stack for swinging a carrier out over the turntable while 55 in the lowered position preparatory to being lifted by the turntable and back into the stack after the record is re-deposited by the turntable upon resuming the lowered position.
20. In a phonograph, a continuously revolvable main shaft, a normally stationary extension shaft, means by which it is set in motion from the main shaft for a predetermined period of revolution, a countershaft, 60 and driving means connecting the extension 65

and countershafts arranged to start the latter after a predetermined period of movement of the extension shaft.

21. A phonograph comprising a turn table, a plurality of record carrier holders 70 at one side of the turn table, means on each of the holders including pairs of abutments providing central recesses, means including a yoke which is arranged to swing in a prescribed zone of movement from the stack 75 toward the turn table, means carried by the yoke including a lug to turn the holders toward the turn table, and means to successively raise the holders so that the recess of each may engage the lug in succession. 80

22. A phonograph comprising a yoke having a single lug and a crank, a shaft upon which the yoke is journaled to swing, a turn table, a plurality of record carrier holders revolvably and slidably carried by the shaft, 85 means on each holder providing a recess, means for periodically sliding all of the holders upon the shaft to bring the successive recesses into registration and engagement with said single lug, and means in 90 connection with said crank for swinging the yoke and rotating the then engaged holder with respect to the shaft and moving the record carrier in the direction of the turn table. 95

23. A phonograph comprising a yoke having a single lug and a crank, a shaft having means by which the shaft is fixed in position and upon which the yoke may turn, means including a sleeve slidable upon the shaft, a plurality of record carrier holders, means including plates having collars by which the holders are mounted upon the sleeve, means associated with the sleeve for periodically sliding the sleeve upon the shaft and moving 100 the holders to registration with the lug successively, each holder having means to be engaged by the lug, and means associated with the crank for turning the yoke and the then engaged holder upon the collar of the 105 respective plate and swinging the record carrier in the direction of the turn table.

24. A phonograph having a fixed hood with an opening and a slot, a yoke situated under the hood and having a single lug, and a crank, a shaft, means carried by the shaft upon which the yoke is journaled to turn, one of said means providing a fastening for one end of the shaft on said hood, means 110 slidable upon the shaft including a sleeve having a support, a plurality of plates having collars fitted on the sleeve and providing a spacing between plates, the lowermost plate resting upon said support, a plurality 115 of record carrier holders mounted upon the respective collars and engaging said hood opening for guidance, each holder having means providing a recess, means associated with said support for periodically sliding the sleeve upon the shaft to bring successive 120

125 means providing a recess, means associated with said support for periodically sliding the sleeve upon the shaft to bring successive 130

recesses into engagement with said single lug and registration with said slot and means associated with the crank for turning the yoke and swinging the holder then in engagement with said single lug within said slot.

25. A phonograph of the character described having a fixed upright shaft, a yoke having the ends journaled upon the shaft, 10 said yoke having a single lug and a crank, a sleeve slideable on the shaft, a plurality of record carrier holders each having means successively engageable with said single lug, means including plates having collars mounted upon the sleeve upon which collars the 15 holders are rotatable, means associated with the crank to turn the yoke and rotate the then engaged holder, and friction means situated between the various holders and 20 plates.

26. A phonograph of the character described having an upright shaft, a plurality of record carrier holders assembled upon the shaft, a plurality of plates having collars 23 upon which the holders are rotatable, a sleeve slideably carried by the shaft upon which the plates are mounted, means at one end of the sleeve upon which said plates and holders are supported, and means including a cover at the opposite end of the 30 sleeve engaging the uppermost collar to hold all of the sleeves together.

27. A phonograph of the character described comprising an upright shaft, a slideable sleeve upon the shaft, a plurality of plates having collars fixed upon the sleeve, said collars spacing the plates apart, a holder 35 revolvably mounted on each collar and being of a thickness less than the distance between 40 plates, washers on each side of the holders filling the remaining space, a wall extending at an angle from each holder at the periphery of an adjoining plate, said wall having an opening, a shelf extending from said wall 45 having an upstanding lug, and record supporting means including a carrier having an opening to receive said lug and a lug to enter the opening in said wall.

28. A phonograph of the character described comprising a stack of record carrier 50 holders, means by which said stack is supported, a rack pendant from the support, a shaft which turns periodically, a dog carried by said shaft to engage a tooth of the 55 adjacent rack and lift the support upon a turn of said shaft, and a back check pawl engaging the rack to support it in each position.

29. A phonograph of the character described comprising a stack of record carrier 60 holders, means by which said stack is supported, a rack pendant from the support, a shaft which turns periodically, a dog carried by said shaft to engage a tooth of the 65 adjacent rack and lift the support upon a

turn of said shaft, and a back check pawl engaging the rack to support it in each position, and means including a pinion carried by the rack to displace the pawl when the rack has reached the extremity of movement in one direction preparatory to returning to the original position.

30. A phonograph of the character described comprising a stack of record carrier 70 holders, means by which said stack is supported, a rack pendant from the support, a shaft which turns periodically, a dog carried by said shaft to engage a tooth of the adjacent rack and lift the support upon a turn of said shaft, a back check pawl 75 engaging the rack to support it in each position, means including a pinion carried by the rack to displace the pawl when the rack has reached the extremity of movement in one direction preparatory to re- 80 turning to the original position, and means including a latch supporting said pawl in the displaced position during the return of the rack.

31. A phonograph of the character de- 85 scribed comprising a stack of record carrier 90 holders, means by which said stack is supported, a rack pendant from the support, a shaft which turns periodically, a dog carried by said shaft to engage a tooth of the 95 adjacent rack and lift the support upon a turn of said shaft, a back check pawl engaging the rack to support it in each position, means including a pinion carried by the rack to displace the pawl when the 100 rack has reached the extremity of movement in one direction preparatory to returning to the original position, means including a latch supporting said pawl in the displaced position during the return of 105 the rack, and means to retard the return of the rack including a piston carried by the rack, a dash pot in which it operates, and a valve associated with the dash pot for controlling the passage of air.

32. A phonograph of the character de- 110 scribed having a stack of record carrier 115 holders, means to support the stack, a rack pendant from the support, a periodically revolvable shaft having a dog to periodically lift the rack to advance the holders to new positions, a back check pawl engaging the rack to support it in each new position, means including a pin on the rack to displace the pawl when the extremity of lifting movement is reached and thereby permit the rack to return, a latch holding the pawl disengaged during said return movement, and means including another pin carried by the rack to displace the latch at the limit of the return movement of the rack thereby to release the pawl for reengagement with the rack.

33. A phonograph of the character de- 125 scribed comprising a turn table, a stack of 130

- record carriers at one side, a periodically revoluble shaft having a cam, means actuated by the cam upon revolution of the shaft to move a record carrier then in position above the turn table back to the stack, and means operated by the continued revolution of the shaft to raise the stack and bring the carrier into a swinging position, said cam operated means then swinging 5 said succeeding carrier out of the stack to position above the turn table at the conclusion of the rotation of said shaft.
34. A phonograph comprising a turn table, a stack of record carriers at one side, means to swing the successive carriers from the stack toward the turn table and vice versa, said means including a yoke having a crank, an intermittently revoluble shaft having a cam, a lever operable by the cam having a link in connection with the crank 20 to swing a carrier then in position above the turn table back into the stack upon initial rotation of the shaft and swing a succeeding carrier from the stack back over the turn table at the conclusion of rotation 25 of said shaft, and means operated by the shaft between said swinging movements to raise the stack and bring the succeeding carrier into a swinging position, said means including a rack associated with the stack 30 and a lifting dog carried by the shaft.

DANIEL DETRICH BEENKEN.
